UNITED STATES PATENT OFFICE

91,522

DESIGN FOR A COMPASS

Julius C. Hochman, New York, N. Y., assignor to
Eagle Pencil Company, New York, N. Y., a cor-
poration of Delaware

Application February 27, 1933. Serial No. 47,330

Term of patent 14 years

To all whom it may concern:

Be it known that I, JULIUS C. HOCHMAN, a citizen of the United States of America, residing at No. 160 Claremont Avenue, New York, New York, have invented a new, original, and ornamental Design for a Compass, of which the following is a specification, reference being had to the accompanying drawing, forming part thereof, in which

Fig. 1 is a plan view, showing my new design;
Fig. 2 a front elevation thereof; and
Fig. 3 a rear elevation thereof.

The dominant characteristic of the compass

design comprises flat legs extending substantially in the radial plane of the compass, each leg widening sharply near the pivoting end thereof, the lower edges of said widened portions superposed to determine in all settings of the compass the rounded shorter base of an equilateral trapezoid, the sides of which are the inner legs of the compass.

I claim:

The ornamental design for a compass, as shown and described.

JULIUS C. HOCHMAN.
